ABSTRACT: A high recovery rate binary counter having high-pressure sensitivity and independence to output loading. The counter embodies a bistable fluid amplifier, two exclusive gates, and a fluid pulse device for providing signal pulses of predetermined duration. The outlet of each exclusive gate is connected to opposing control ports of the bistable fluid amplifier while the input to the exclusive gates is connected to the outlet of the pulse device. Feedback is provided from the outlets of the bistable fluid amplifier to the control ports of the exclusive gates. A second embodiment employs AND gates in place of exclusive gates.

BINARY COUNTER

BACKGROUND OF THE INVENTION

Although fluidic binary counters have been shown, such as those where a pair of bistable fluid amplifiers are cascaded, such prior art counters did not have sufficient pressure sensitivity, were not independent of output loading, required well defined input pulses, and the like. As is readily seen, such counters provided many disadvantages in practical applications.

A bistable "lockon" type fluid amplifier is one where the fluid power stream or input pulse locks on to one wall or the other of an interaction chamber and the power stream is directed substantially entirely to one or the other of a pair of outlet passages in response to fluid signals applied to the control nozzles thereof.

An exclusive gate is a fluidic device wherein a power stream is intercepted by a single outlet passage. The device has a control nozzle such that the stream can be deflected from the outlet passage and vented.

An AND gate is fluidic device wherein a power stream is embodiment directed to one of two outlets. The stream is deflected to the other outlet when fluid pulses are received at the control nozzle thereof from two sources.

A fluid pulse device may be one such as that described in Pat. application Ser. No. 550,284 in the name of R. H. Bellman and T. W. Bermel. It may also be any fluid pulse device wherein a pulse of a finite duration may be obtained in response to a signal having an duration in excess of the predetermined output pulse.

SUMMARY OF THE INVENTION

The objects of the present invention are to provide a simple direct rugged, and inexpensive fluidic binary counter having high pressure sensitivity, does not require a well define input signal pulse, is independent of output loading, and one which overcomes the hereinabove noted disadvantages.

Briefly, according to the present invention a high recovery rate binary counter is provided comprising a bistable fluid amplifier and a pair of exclusive gates the outlets of which are connected to opposing control nozzles of the bistable fluid amplifier. The inlets of the exclusive gates are connected to a suitable fluid pulse device. A portion of the fluid passing through the outlets of the bistable fluid amplifier is fed back to the control nozzles of the exclusive gates.

Also described is an alternative circuit wherein a pair of AND gates are substituted for the exclusive gates.

Additional objects, features, and advantages of the present invention will become apparent to those skilled in the art from the following detailed description and the attached drawings on which, by way of example, only preferred embodiments of this invention are illustrated.

BRIEF DESCRIPTION OF THE DRAWINGS

FIG. 1 is a schematic diagram of one embodiment of the binary counter of the present invention.

FIG. 2 is a schematic diagram of another embodiment of the binary counter of the present invention.

DETAILED DESCRIPTION

By the term fluid as used herein is meant by compressible fluid such as air, nitrogen, or other gases or incompressible fluid as water or the like, which fluids may contain solid particles. The invention is not limited to any particular fluid.

FIG. 1 illustrates an embodiment of the fluid operated binary counter of the present invention which includes a bistable fluid amplifier 10 and a pair of exclusive gates 12 and 14. Fluid amplifier 10 comprises power stream or inlet nozzle 16, a pair of outlet passages 18 and 20, and four controls nozzles 22, 24, 26, and 28. The inlet nozzle 16 of bistable fluid amplifier 10 is connected to a suitable source 30 of fluid. Exclusive

gate 12 has an inlet nozzle 32, an outlet passage 34 and a control nozzle 36. Exclusive gate 14 has an inlet nozzle 38, an outlet passage 40 and a control nozzle 42.

A fluid pulse device 44 is one which provides a fluid signal of a finite and determinable length of time at outlet passage 46. Signals are provided by source 48 and are applied in part to control nozzle 50 and in part through delay line 54 to control nozzle 52. A power stream is emitted from power stream inlet 56 and ordinarily passes through outlet passage 58. Fluid pulse device 44 is similar to that described in the heretofore noted Bellman and Bermel patent application.

Outlet passage 46 of fluid pulse device 44 is connected to inlet nozzles 32 and 38 of exclusive gates 12 respectively 15 and 14 respectively by means of a passage 60. Control nozzle 36 of exclusive gate 12 is connected to the opposing outlet passage 29 of bistable fluid amplifier 10 by means of passage 62 and control nozzle 42 of exclusive gate 14 is connected to the opposing outlet passage 18 of fluid amplifier 10 by means of passage 64.

Outlet passage 20 of bistable fluid amplifier 10 is connected by means of passage 66 to a suitable utilization device 68 such as the binary counter indicator means. Such an indicator means may be a spring-loaded flag device which counts and indicates the number of fluid pulses received. Passage 70 is connected to outlet passage 18 of bistable fluid amplifier 10 and would ordinarily be connected to the next counter stage, not shown. The fluid flow in passage 70 would serve as the input to the next stage.

The operation of the binary counter of FIG. 1 is as follows. A fluid pulse device 44 is provided wherein a power stream is passed from a suitable source through inlet 56 and caused to be emitted through outlet passage 58. The device is a monostable one wherein the power stream will continue to pass through outlet passage 58 unless deflected to outlet passage 46 by means of a signal emitted through control nozzle 50. When a signal is provided from source 48 a portion of it is emitted through control nozzle 50 causing the power stream to be deflected to outlet passage 46 while the other portion of said signal is caused to traverse through delay line 54 and be emitted through opposing control nozzle 52. When the second portion of the signal reaches control nozzle 52 and is emitted therefrom, the power stream flips over and again passes through outlet passage 58. The duration of the pulse emitted through outlet passage 46 is determined by the difference in time that it takes the first portion of the signal to be emitted through control nozzle 50 and the time that it takes the second portion of the signal to traverse delay line 54 and be emitted through control nozzle 52. As is readily seen, the duration of the pulse emitted from outlet passage 46 is controlled to a preselected interval by controlling the length of the passages leading to control nozzles 50 and 52.

A power stream provided by source 30 is emitted through inlet nozzle 16 of bistable fluid amplifier 10. For the purposes of this description it is assumed that initially, this power stream will pass through outlet passage 18. As a fluid signal is received from source 48 a pulse of predetermined duration is emitted through outlet passage 46. This pulse is transmitted through passages 60 to inlet nozzles 32 and 38 of exclusive gates 12 and 14 respectively. Since the power stream emitted through inlet nozzle 16 of the bistable fluid amplifier 10 is being emitted through outlet passage 18, a portion thereof is bypassed by means of passage 64 to control nozzle 42 of exclusive gate 14. The portion of the pulse emitted through inlet nozzle 38 of exclusive gate 14 will be deflected by the feedback flow through control nozzle 42 and be vented to atmosphere. The portion of the pulse emitted through inlet nozzle 32 of exclusive gate 12 will enter outlet passage 34 of exclusive gate 12 and be emitted from control nozzle 22 of bistable fluid amplifier 10. This portion will not be deflected since no fluid is being emitted by control nozzle 36 of exclusive gate 12 at this point in time. As the pulse is emitted through control nozzle 22 of fluid amplifier 10, the power stream emitted from inlet nozzle 16 is caused to flip over from outlet passage 18 to

outlet passage 20, whereupon the flow through feedback passage 64 is terminated and a similar feedback is caused to flow through feedback passage 62 to control nozzle 36 of exclusive gate 12. The remainder of the flow through passage 66 will pass to and be caused to be sensed by utilization device 68.

When the next pulse is transmitted through outlet passage 46 of fluid pulse 44 it will similarly pass through both sections of passages 60 and be emitted through inlet nozzles 32 and 38 of exclusive gates 12 and 14 respectively. This time, however, that portion of the pulse emitted from inlet nozzle 32 will be deflected by the feedback flow emitted through control nozzle 36 of exclusive gate 12 and be vented, whereas that portion of the pulse emitted through inlet nozzle 38 of exclusive gate 14 will be intercepted by outlet passage 40 and be emitted through control nozzle 26 of bistable fluid amplifier 10. In this manner, the power stream emitted from inlet nozzle 16 of amplifier 10 will flop over from outlet passage 29 to outlet passage 18 whereupon the cycle will commence all over again.

Referring again to FIG. 1 it is seen that a pair of second control nozzles 24 and 28 are provided in bistable fluid amplifier 10 for setting and resetting the binary counter in the present invention. For the purposes of the present description, it is assumed that "0" is represented when the fluid passes through passage 70 and "1" is represented when the fluid stream passes through passage 66 to utilization device 68. When it is desired to reset the counter to "0" signal is provided from a suitable source, not shown, through reset control nozzle 28 of fluid amplifier 10. This will cause the power stream emitted from the inlet nozzle 16 to either remain passing through outlet passage 18 or be flipped over to outlet passage 18 from outlet passage 20 if it happens to be flowing in outlet passage 20. On the other hand, when it is desired to preset the binary counter, a fluid set signal is provided from a suitable course, not shown, through set control nozzle 24. This procedure will cause the power stream emitted from inlet nozzle 16 to either continue flowing through outlet passage 20 or be flipped over from outlet passage 18 to outlet passage 20 if the stream originally flowing in outlet passage 18. In this manner, the utilization device will sense a signal representing "1."

It should be noted that fluid pulse device 44 must provide a pulse of duration which is less than the total of the switching time of bistable fluid amplifier 10 and feedback time through passages 62 and 64 to prevent oscillation of the counter.

Another embodiment of the present invention is illustrated in FIG. 2 wherein the exclusive gates of FIG. 1 are replaced by AND gates 72 and 74. AND gate 72 has an inlet nozzle 76, a pair of outlet passages 78 and 80, and a control nozzle 82. The power stream provided by a suitable source 83 is emitted through inlet nozzle 76 and ordinarily will flow in outlet passage 80. Control nozzle 82 is connected to two sources of signals and the device is designed such that a signal from both sources must be present in order to deflect the power stream from outlet passage 80 to AND outlet passage 78. Outlet passage 80 is vented while outlet passage 78 is connected to control nozzle 22 of bistable fluid amplifier 10. One control signal flow is provided by means of feedback passage 84 connected intermediate outlet passage 18 of bistable fluid amplifier 10 and control nozzle 82 of AND gate 72. The other source of control signal flow is provided by means of fluid pulse device 44 through passages 86.

Similarly, AND gate 74 has an inlet nozzle 88, a pair of outlet passages 90 and 92 and a control nozzle 94. Outlet passage 92 of AND gate 74 is vented while AND outlet passage 90 is connected to control nozzle 26 of bistable fluid amplifier 10. Control nozzle 94 of AND gate 74 is connected to both outlet passage 20 of bistable fluid amplifier 10 through feedback passage 96 and the outlet of fluid device 44 by means of passage 86. Inlet nozzle 88 is connected to a suitable source 97 of fluid.

The operation of this embodiment of the binary counter of the present invention is as follows. For the purposes of this description it is assumed that initially the power stream

emitted from inlet nozzle 16 will pass through outlet passage 18. Accordingly, a portion of this power stream will be bypassed by means of feedback passage 84 and be emitted through control nozzle 82 of AND gate 72. An AND gate is designed such that the power stream emitted from inlet nozzle 76 will be emitted through outlet passage 80 unless a signal is received at control nozzle 82 from two sources whereupon the power stream will be deflected to AND outlet passage 78. Accordingly, when a fluid pulse is provided by means of fluid pulse device 44 it is transmitted through passages 86 to control nozzles 82 and 94 if AND gate 72 and 74 respectively. Since AND gate 74 requires a signal from fluid pulse device 44 and a feedback signal from outlet passage 20 of bistable fluid amplifier 10 before its power stream is deflected from outlet passage 92 to AND outlet passage 90, it will be unaffected by the portion of the fluid pulse provided by device 44 alone. On the other hand, when the portion of the fluid signal from device 44 is passed through control nozzle 82 of AND gate 72 it combines with the feedback pulse passed through passage 84 and causes the power stream of AND gate 72 to flop over from outlet passage 80 to AND outlet passage 78 whereupon it is transmitted through control nozzle 22 of bistable fluid amplifier 10. At this point, the power stream passing through outlet passage 18 of fluid amplifier 10 will flop over to outlet passage 20 whereupon a portion thereof will be fed back by means of feedback passage 96 to control nozzle 94 of AND gate 74. When the next pulse is provided by fluid pulse device 44, it will not affect the flow through AND gate 72 as heretofore described however, it will combine with the feedback signal passing through passage 96 and will be emitted through control nozzle 94 of AND gate 74 causing the power stream to flip over from outlet passage 92 to AND outlet passage 90. This signal will pass through control nozzle 26 of fluid amplifier 10 and cause the power stream to be deflected from inlet passage 20 to outlet passage 18. Utilization device 68 will sense these pulses as heretofore described providing a count thereof.

It is understood that only one stage of a fluid operated binary counter has been described herein and where higher counting levels are desired a plurality of interconnected stages will be required as known in the art.

One familiar with the art will readily understand that the final design parameters of specific fluid devices will at least be dependent upon the fluid density, temperature, and pressure as well as the characteristics of the outlet stream at the point of utilization.

Although the present invention has been described with respect to specific details of certain embodiment thereof, it is not intended that such details be limitations upon the scope of the invention.

I claim:

1. A fluid-operated binary counter comprising:
a bistable fluid amplifier having an inlet nozzle, a pair of outlet passages and a plurality of control nozzles;
a first exclusive gate having an inlet nozzle, a control nozzle, only one outlet passage, and vent means;
the outlet passage of said first exclusive gate being connected to one of the control nozzles of said bistable fluid amplifier;
- 55 a second exclusive gate having an inlet nozzle, a control nozzle, only one outlet passage, and vent means;
the outlet passage of said second exclusive gate being connected to a control nozzle of said bistable fluid amplifier in opposition to said one control nozzle;
- 60 a fluid pulse device having one outlet passage connected to the inlet nozzles of both the first and second exclusive gates for providing fluid signal pulses thereto;
- 65 a first feedback passage connected intermediate the control nozzle of said first exclusive gate and the opposing outlet passage of said bistable fluid amplifier; and
- 70 a second feedback passage connected intermediate the control nozzle of said second exclusive gate and the opposing outlet passage of said bistable fluid amplifier.

2. The fluid-operated binary counter of claim 1 further comprising a utilization device.
3. The fluid operated binary counter of claim 1 further comprising means for resetting the counter.
4. The fluid-operated binary counter of claim 3 wherein said means for resetting comprise a source of fluid pulses connected to a control nozzle of said bistable fluid amplifier.
5. The fluid operated binary counter of claim 1 further comprising a means for setting said counter.
6. The fluid-operating binary counter of claim 5 wherein said setting means comprise a source of fluid signals connected to a control nozzle of said bistable fluid amplifier.
7. The fluid-operated binary counter of counter of claim 1 further comprising means for resetting said counter and means for setting said counter.
8. The fluid-operated binary counter of claim 7 further comprising a utilization device.
9. A fluid-operated binary counter comprising:
- a bistable fluid amplifier having an inlet nozzle, a pair of outlet passages, and a plurality of control nozzles;
- first and second AND gates each having an inlet nozzle, a control nozzle suitable for connection to two sources of

- fluid signals, an AND outlet passage, and a second outlet passage;
- the AND outlet passage of the first AND gate being connected to one control nozzle of said bistable fluid amplifier while the AND outlet passage of the second AND gate being connected to the opposing control nozzle of said bistable fluid amplifier;
- a fluid pulse device having one outlet passage connected to the control nozzles of both the first and second AND gates for providing fluid signal pulses thereto;
- a first feedback passage connected between the control nozzle of said first AND gate and the corresponding outlet of said bistable fluid amplifier; and
- a second feedback passage connected field of control nozzle of said second AND gate and its corresponding outlet passage of said bistable fluid amplifier.
10. The fluid-operated counter of claim 9 further comprising means for resetting and setting said counter.
11. The fluid-operated counter of claim 10 further comprising a utilization device.
